SHEET FEEDING MEANS

Clair D. Lake, Binghamton, N. Y., assignor to International Business Machines Corporation, New York, N. Y., a corporation of New York

Application June 11, 1936, Serial No. 84,676

13 Claims. (Cl. 235—61.9)

This case relates to means for feeding a record sheet on which a record is made by a tabulating machine under control of record cards.

The record cards are perforated according to a selected code to represent information. The cards are arranged in groups and are fed through the machine in succession. The machine has tabulating cycles during which items from a card being analyzed are entered in accumulators and also listed on the record sheet. When a card group change occurs, a total of the items accumulated from the group of cards which has last passed through the machine is printed on the record sheet.

For printing information such as the data of a bill or invoice, each group of cards includes some which contain the head data; that is, the data which makes up the heading of the bill; for example, the name and address. The remaining cards of the group contain the data to be filled as, for example, articles sold and their price. The latter data may be referred to as the detail data. The total data are the accumulation, say of the individual prices of the articles.

It is desirable to print the head, detail, and total data within predetermined portions of a bill form. The bill forms may be pre-printed with indicia for classifying the information printed under control of the record card. The successive bill forms may be separated by a perforated line or the forms may be in a continuous sheet uninterrupted by perforated lines and may be cut into individual forms later.

An object of the invention is to provide improved means for printing the head data in a predetermined location of the sheet.

Another object is to provide improved means for printing the first detail item on a definite line of the sheet at a predetermined line spacing from the head data.

Still another object is to print the total data on a predetermined line of the sheet.

An object also is to provide for overflow of detail data on one bill form by automatically feeding the first detail line of the next bill form to the printing position to receive the first overflow item, and to also print the total on the predetermined total line of the latter bill form.

Still another object is to provide sheet feeding means powered by a motor separate from the tabulating machine.

Ancillary to the latter object is the provision of sheet feeding means in the form of an attachment removable at will from the tabulat-

ing machine without disturbing the tabulating equipment.

It is also an object to provide a reciprocatable sheet feeding device controlled by the tabulating machine.

A further object is to provide means for causing the sheet feeding device to feed the sheet on the forward stroke and to return without influence on the sheet.

Auxiliary to the latter object is the provision of means to hold the sheet against movement while the feeding device is returning to the starting point.

The object is further to provide a feeding device comprising a rectilinearly movable carriage with grippers to clamp the sheet and advance it with the carriage.

Auxiliary to the latter object is the provision of electrical, magnetic, means to operate the grippers.

The invention also includes spacing controls to control the amount of forward movement of the carriage and the corresponding feed of the sheet to bring the successive portions of the sheet to printing position.

The invention in the spacing controls contemplates provision of a line spacing control to control sheet feed from one line space to the next; also the provision of a head and total space control to determine the feed of the sheet to the proper positions for receiving head or total printing; and also provision of an overflow control to determine the feed of the sheet in the event the number of detail items exceeds the space allotted thereto on one bill form.

Further, an object of the invention is to prevent initiation of a machine cycle until movement of the sheet feeding carriage has been completed.

More specifically, the latter object contemplates means to prevent initiation of a machine cycle until an overflow feed has been completed.

Further, means are provided to prevent initiation of a machine cycle until a reverse movement of the feeding carriage is completed.

Further, the object is to prevent the initiation of a total taking operation until the total line of the sheet is in printing position.

Likewise, the object is to prevent initiation of a new series of tabulating operations following a total print cycle until the first line of the head portion of the next bill form is in printing position.

Other objects will appear from the following

parts of the specification and from the drawings, in which:

Fig. 1 is a side view of the printing and sheet feeding mechanism;

5 Fig. 1a is a detail of the tabulating machine showing the list cam contacts, and their operating means;

Fig. 2 is a plan view of the sheet feeding means;

10 Figs. 3, 4, 5, 6, and 7, are respectively sections taken along lines 3-3, 4-4, 5-5, 6-6, and 7-7 of Fig. 2;

Fig. 8 is an enlarged, partly sectional, detail view of the driving mechanism of the sheet feeding means;

15 Fig. 9 diagrammatically illustrates the contour of the spacing control bars in relation to the information printed on a plurality of bill forms;

20 Fig. 10 is a timing diagram;

Fig. 11 shows part of the circuit of the tabulating machine, and

25 Fig. 11a, which is a continuation of Fig. 11, shows the circuit of the sheet feeding mechanism.

The invention is applicable to any suitable recording machine in which a sheet or the like is to be fed, but is preferably applied to a card-controlled tabulating machine, which may be one 30 such as shown in either Patent No. 1,965,975 or 1,976,617. For purposes of the disclosure, the invention will be explained in connection with the machine disclosed in Patent 1,976,617, and the following parts of the description will refer 35 to elements of the latter machine by the same reference characters as in the patent, while other elements may be referred to as special and will be given other reference characters.

As disclosed in Patent 1,976,617, the machine 40 goes through tabulating cycles and total taking cycles. In a tabulating cycle, the cards are fed, entries into accumulators are made under control of one of the cards, and printing is effected, assuming the machine to be set for listing. The 45 cards are arranged in major and minor groups, the major group including several minor groups. When either the major or minor group changes, the machine goes through a total taking cycle during which the total of items standing on 50 accumulators is printed and the accumulators reset.

Near the end of a total taking cycle, cam contacts P7 and P8 close to form the following minor control circuit (Fig. 11):

55 Circuit a—Minor control

From the left side of the line, through contacts P7, contacts P8, minor control relays 366 and 367, line 368, motor control relay 328, line 60 369, cam contacts L10, cam contacts L9, line 363, and to the right side of the line.

Simultaneously, a major control circuit is formed:

65 Circuit b—Major control

From the left side, through cam contacts P7, major control relay 370, cam contacts L9, line 363, and to the right side.

70 Circuit a energizes relay 366 to close holding contacts 366a which by-pass cam contacts P7 and P8. Similarly, circuit b energizes relay 370 to close contacts 370a to by-pass cam contacts P7.

Circuit a also energizes relay 328 to close contacts 328a for normally establishing the follow-

ing auto start circuit when cam contacts P2 close near the end of the total print cycle (Fig. 11):

5 Circuit c—Auto start

From the right side, through contacts 338a, stop key contacts SP, lower card lever relay contacts UCLA (now closed), cam contacts P2, normally closed special relay contacts H-1, auto start switch 353 (closed), relay 339, contacts 27, 10 tabulating clutch magnet 22, cam contacts P1, and to the left side.

Energization of magnet 22 opens contacts 27 to shunt the circuit through relay 340. The relay 340 is energized, closes contacts 340a and 15 forms a circuit through motor TM which sets the latter in operation.

With tabulating clutch magnet 22 energized and the tabulating motor TM running the machine goes through a tabulating cycle.

20 After cam contacts P2 open, circuit c is maintained through a by-pass circuit path c1 which extends from the stop key contacts SP, through relay contacts 339c (now closed), upper card lever relay contacts UCLA, special relay contacts 25 I-2, line 345, relay contacts 339a, relay 339, and as before in circuit c.

Another shunt path c2 for relay 339 and tabulating clutch magnet 22, which by-passes motor control relay contacts 338a, extends from the 30 right side of the line, through cam contacts L2, special relay contacts I-2, line 345, and as before in shunt path c1 and circuit c.

The purpose of the shunt path through cam contacts L2 is to maintain the tabulating motor 35 in operation and cause completion of a tabulating cycle after contacts 338a open as a result of a change in card group.

During the first tabulating cycle, the first card of a group is fed to the upper analyzing brushes 40 UB (Fig. 11). During the second tabulating cycle, the first card is fed to the lower analyzing brushes LB. During the third tabulating cycle, the first card moves past the lower brushes LB. Concurrently, the second card is passing the 45 upper brushes UB. Corresponding brushes UB and LB sense the group control items of the pair of cards. These corresponding brushes are plugged to opposite sides of duo control relays 359-360. If agreement of group designating 50 perforations is found, then the control relays are energized, contacts 359b are closed during the cycle, and then held closed while cam contacts L9 and L10 of circuits a and b open, which occurs after the item analyzing period "9" to 55 "11" (see the timing diagram, Fig. 10).

Minor group control circuit a is then maintained through a shunt path around contacts L9 and L10 as follows: From the lower blade of contacts L10 (now open), through line 369, serially connected contacts 359a (now closed), plug wire 321, upper card lever relay contacts UCLA, line 363, and to the right side of the line.

Major control circuit b is maintained through a shunt path which extends from the lower blade 65 of contacts L9, through plug wire 320, the serially connected contacts 359b above wire 320, plug wire 321, contacts UCLA, and as before.

In above manner, whenever the upper and lower cards are found by brushes UB and LB to have the same group classification items, then the minor and major group control circuits remain energized. When the last card of a minor group is passing the lower brushes, then the first card of the next group is passing the upper 75

brushes. Disagreement of minor group classification items will be found, one of contacts 359b below plug wire 320 (Fig. 11) will not close, and when cam contacts L9, L10 open, circuit a will break thereby detecting a minor group change. Similarly, if a major group change occurs, then one of contacts 359b above plug wire 320 will be open, and when contacts L9 and L10 open, both circuits a and b will break.

10 When circuit a breaks, motor control relay 338 is deenergized and contacts 338a open while contacts 338b close.

15 Opening of contacts 338a breaks the tabulating circuit path c1 and when cam contacts L2 open to break shunt path c2, then tabulating operations cease and the cards stop feeding.

The closing of contacts 338b normally forms the following auto reset circuit (Fig. 11).

20 *Circuit d—Auto reset*

From the right side of the line, through contacts 338b, auto reset switch 346 (closed), special normally closed relay contacts H—2, cam contacts L3, relay 348, cam contacts P3, and to the left side of the line.

Circuit d energizes relay 348 to close relay contacts 348a, leading current directly from the right side of the line through relay 348, which remains energized until cam contacts P3 open.

25 30 Closing of relay contacts 348a also forms the following circuit:

Circuit d—1: Reset clutch

From the right side of the line, through contacts 348a, cam contacts L4, reset clutch magnet 197, normally closed relay contacts 384c, contacts P3, and to the left side of the line.

Circuit d—1 energizes reset clutch magnet 197. Energization of magnet 197 causes contacts 287 to close and form a circuit through the reset motor RM, as follows:

Circuit e—Reset motor

From the left side of the main line, through reset motor RM, relay 350, line 351, contacts 287, line 352, and to the other side of the main line.

Circuit e sets the reset motor in operation and with the reset clutch magnet energized, the machine now goes through a total print and reset cycle, during the first half of which the total printing operation is effected and during the latter half of which the accumulators are reset.

Near the end of the reset cycle, circuits a and b through the major and minor control relays 370 and 366, 367 and through motor control relay 338 are reestablished. As a result of energization of relay 338, contacts 338a close again to form auto start circuit c.

60 65 During tabulating cycles, the lower card analyzing brushes LB sense the items on the cards, and energize add magnets 11 (Fig. 11) to enter the items into accumulators. At the same time, operation of the accumulators correspondingly sets total read-out commutators 110—111—112. In the present case, the machine is set for listing, so that the lower brushes LB when they sense items in the cards to control add magnets, also simultaneously energize print magnets 223 (see Figs. 1 and 11) to control the positioning of type carriers 212.

70 75 During total print and reset cycles, print magnets 223 are energized through an emitter 279—280—281 and the total read-out commutators 110—111—112 to position type carriers 212 for

printing the total of items entered in the accumulators under control of the group of cards which has just passed through the machine. After the total is printed, the accumulators and the total read-out commutators are reset to zero.

Referring to Fig. 1, type carriers 212 carry type 218 mounted for transverse movement relative to the type carriers. When the carriers 212 are selectively raised under control of print magnets 223, one of the type 218 is located at printing 10 position in front of a special platen 500 rotatably carried by a special shaft 501. At the end of the type carrier positioning portion of either the reset or tabulating cycle, a hammer 224 is operated to strike the type element 218 at printing 15 position and cause the latter, through the usual ink ribbon, to print on the record sheet RS.

The following parts of the description will be concerned mainly with the feeding and spacing mechanism of record sheet RS.

The mechanical construction of the feeding and spacing mechanism will be described first.

Shaft 501, on which platen 500 is rotatably carried, is mounted on a special bracket 502 secured to the frame 503 of the printing section 25 of the tabulating machine. Removably secured to frame 503 is the frame 504 of the feeding and spacing attachment.

The right hand or rear end of the frame 504 mounts a motor M, the shaft 505 of which has 30 a large gear 506 and a small gear 507 (see Fig. 6). The large gear 506 meshes with a gear ring 508 fixed to the periphery of a magnetic clutch disk 509 (Figs. 1 and 8) rotatably mounted on a shaft 510. The small gear 507 acts through an 35 idler gear 511 to drive a gear ring 512 fixed to the periphery of another magnetic clutch disk 513 also rotatably mounted on shaft 510.

Mounted in recesses of clutch disks 509 and 513 are the exciting coils 514 and 515. Between 40 the clutch disks is located a driven clutch wheel 516 keyed to shaft 510 to rotate therewith while being permitted to slide axially between disks 509 and 513. When coil 514 is energized, the wheel 516 is shifted to the left (Fig. 8) and clutched 45 to disk 509 for rotation. Shaft 510 is then driven by motor M through gears 506 and 508, disk 509, and wheel 516.

When coil 515 is excited, then wheel 516 is shifted to the right and clutched to disk 513 50 for rotation. Shaft 510 is then driven by motor M through gears 507, 511, 512, disk 513, and wheel 516.

Gearing 507, 511, and 512 rotates disk 513 at half the speed at which disk 509 is rotated by 55 gearing 506, 508 and in the opposite direction. Thus, when shaft 510 is coupled to disk 513, it is driven at half the speed and in the opposite direction as when coupled to disk 509.

Shaft 510 extends along the left hand side of frame 504 (as viewed from the rear). The shaft is journaled at opposite ends in the frame and carries a worm 518 keyed to the shaft by a key bar 519 (see Figs. 1, 7, and 8). The worm thus rotates with the shaft but is capable of free 60 sliding movement along the shaft.

Straddling the opposite ends of worm 518 are the legs 520 of a bifurcated depending side 521 of a traveling carriage 522. The carriage extends across the width of frame 504 and at opposite 70 sides carries rollers 523 riding on rails 524 fixed to the frame and disposed exteriorly of and along opposite sides of the frame (see Figs. 1, 2, 3, and 7).

75 Journaled between the opposite sides of the 75

carriage 522 is a cross shaft 525 carrying pinions 526 at opposite ends meshed with racks 527 fixed to frame 504 and extending, parallel to rails 524, along opposite sides of the frame. Adjacent side 5 521 of the carriage, shaft 525 rigidly carries a worm wheel 528 (Figs. 1 and 8) meshed with worm 518. Rotation of shaft 510 rotates worm 518 which, in turn, rotates worm wheel 528 to rotate shaft 525. Pinions 526 of shaft 525 there- 10 upon rotate and as they do so, being meshed with fixed racks 527, roll along the racks. This causes shaft 525 and the carriage 522 to correspondingly move with pinions 526 longitudinally of shaft 510 and of frame 504. As the carriage moves 15 longitudinally, the legs of its side 521 force worm 518 to move with the carriage and slide along shaft 510.

As explained before, clutch disk 513 rotates shaft 510 in the opposite direction to which it is 20 rotated by clutch disk 509. When rotated by clutch disk 513, shaft 510 drives carriage 522 from left to right (as viewed in Fig. 1) or in a forward direction. Clutch 513—515 may, therefore, be referred to as the advance clutch. When 25 shaft 510 is rotated by clutch disk 509, the shaft drives carriage 522 in an opposite or reverse direction. Clutch 509—514 may, therefore, be termed the reverse clutch. Further, the shaft is rotated twice as fast by the reverse clutch as 30 by the advance clutch. Therefore, the carriage is driven twice as fast in the reverse direction as in the forward direction.

Carriage 522 carries a pair of transversely spaced sheet gripping assemblies TG. Each assembly 35 comprises a U-shaped housing 530 fixed to the front and upper cross web 522' of the carriage. Each housing 530 encloses a solenoid 531 rigidly mounted on web 522'. The plunger 532 of the solenoid is connected by a link 533 (see particularly Fig. 4) to the pivot of a pair of toggle links 534 and 535. Link 534 is pivoted at its upper end on shaft 536 carried between the sides of housing 530. Link 535 is pivoted at its lower end to an arm 537 journaled at the rear on a shaft 538 carried between the sides of housing 530 and pivotally carrying at its forward end a clamp shoe 540, faced with rubber gripping blocks 541. The two jaws 540 of the two gripping assemblies are located above the upper surface of cross bar 542 of the carriage.

When the solenoids 531 are energized, their plungers 532 move to the left (Fig. 4) and straighten the toggle linkages 534—535 against resistance of springs 543. As the toggle linkages straighten, they depress arms 537 to move clamp shoes 540 down towards bar 542 of the carriage. The sheet RS is thereby clamped tightly between the jaws 540 and the top of bar 542, and is thereafter constrained to move with the carriage 522. 60

A similar pair of stationary gripper assemblies SG is fixed to the frame 504 at the rear or right hand end, as viewed in Figs. 1 and 3. The stationary gripper assemblies SG are alike in every essential respect with the traveling gripper assemblies TG. Solenoids 544 of the stationary grippers, when energized, depress clamp shoes 545 of the stationary gripper assemblies to clamp the sheet RS against the top of the rear cross bar 546 of frame 504.

Contact rails 547 extend longitudinally of frame 504 and are carried by but insulated from the front cross bar 548 and the rear cross bar 546 of the frame. Cross bar 542 of the carriage carries, through insulation, spring wipers 549, each

riding on one of the contact rails 547. From two of these feelers suitable leads are directed to opposite sides of the coils of solenoids 531 of the traveling grippers.

At the right hand side, as viewed from the rear 5 or in Fig. 7, the carriage 522 rigidly carries a plate 550 which through insulation rigidly supports three parallel spring blades 551, 552, and 553. Also rigidly supported by plate 550 through insulation are three spaced, parallel, legs 554. 10 These legs pivotally mount three levers 555, 556, and 557. Lever 555 faces blade 551 and at the upper end is provided with a contact point 558 companion to the contact point 558 carried by blade 551. Lever 555 also has an insulating stud 15 555' (see Fig. 5) engaging a blade 555a facing a blade 551a. Between them, blades 555a and 551a carry companion contact points 558'. Similarly, lever 556 and blade 552 carry companion contact points 559, and lever 557 and blade 553 20 carry companion contact points 560. Suitable leads are directed from feelers 549 of contact rails 547 to the contacts 558, 558', 559, and 560 to connect the latter into the circuits to be described. 25

At their lower ends, levers 555, 556, and 557 are provided with rollers 562 of insulating material. Fixed to frame 504 and extending along the side thereof below the three rollers 562 are 30 three rails 563, 564, and 565 (see Figs. 2, 5, and 7).

Roller 562 of lever 555 rides on rail 563 which has elongated notches 563' (see also Fig. 9). Roller 562 of lever 556 rides on rail 564 which has a series of notches 564'. Roller 562 of lever 557 35 rides on rail 565 which is formed with a series of short, equally spaced, notches 565'. As will be brought out later, rail 563 controls spacing in the event of an overflow of detail items on a single bill form, and may be termed the overflow bar. Rail 564 controls spacing from the last head 40 item to the first detail item and also spacing from the last detail item to the total line, and may be termed the Head and Total space bar. Rail 565 determines single line spacing of the carriage, and may be called the line spacing bar. 45 Whenever a notched portion of the feed-controlling bars 563, 564 or 565 underlies the coating roller 562, the associated lever 555, 556, or 557 is permitted to rock counterclockwise (Fig. 5) under the influence of individual spring 567 to 50 respectively close overflow contacts 558 and 558', total and head space contacts 559, or line space contacts 560. The manner in which these contacts control carriage travel will be explained 55 later in connection with the circuit diagram, Fig. 11a.

The left side of carriage 522 is provided with an adjustable screw 570 in line with an insulating stud on a spring blade 571 secured through insulation to the front end of frame 504 and carrying one of the companion points of contacts 572, the other point of which is on a spring blade 573 similarly fixed to frame 504. Normally, contacts 572 are open. When the carriage is at the 60 beginning of its forward travel; that is, when the carriage is in extreme forward position, screw 570 acts on blade 571 to close contacts 572. The latter may be referred to as the front rail contacts. 65

A pair of spring blades 574 and 575 carrying between them contacts 576 are mounted on the rear end of frame 504. Normally, contacts 576 70 are closed. When the carriage reaches the end of its forward stroke; that is, when it is in ex- 75

treme rear position, a member 577 on the carriage engages blade 574 to open contacts 576. The latter may be referred to as the rear rail contacts.

5 The arms 537 of the traveling gripper shoes 540 are provided with handles 578 whereby the shoes 540 may be raised at will.

To the left of the magnetic clutch assembly, frame 504 fixedly carries a magnetic brake disk 580 freely surrounding shaft 510. The exciting coil 581 of disk 580 faces a disk 582 keyed to shaft 510. When coil 581 is energized, disk 582 is attracted towards disk 580 and by engagement with the latter is braked to bring shaft 510 and the carriage 522 driven thereby to an immediate stop.

To connect the exciting coils 514 and 515 of rotating magnetic clutch disks 509 and 513 into the circuit, to be described later, each of disks 509 and 513 carries, through insulation, a pair of collector rings 585 and 586 (see Fig. 8). Each of the collector rings of a pair is connected to one of the opposite sides of the exciting coil of the magnetic disk which carries the collector rings. A brush holder 587 carried by frame 504 mounts two pairs of brushes 588 and 589, the former wiping the smaller collector rings 585 and the latter the larger collector rings 586. The brushes are suitably connected into the circuit and conductively connected through the collector rings to the exciting coils 514 and 515.

The plunger 532' of one of the stationary gripper assemblies SG is provided with a pin 532a to engage a spring blade 590. Blade 590 carries one of the contacts 591, the companion contact of which is on a spring blade 592. Contacts 591 may be referred to as the stationary gripper contacts. When the solenoids 544 of the stationary gripper are deenergized and, therefore, when the clamp shoes 545 are not gripping the record sheet RS, then pin 532a is engaging blade 590 to close contacts 591. When the solenoids 544 are energized, and clamp shoes 545 are gripping the paper, then pin 532a retreats and permits contacts 591 to open.

45 The sheet RS is led around a guide 601 carried by frame 504, then above a flat plate 603 secured to the frame 504 and spanning the width of the frame, and between tensioning rollers 604 and platen 500, then around the platen, between the clamp shoes 540 of the traveling gripper and cross bar 542 of carriage 522, and from there between the clamp shoes 545 and the top of rear cross bar 546 of the frame 504.

The mechanical features of the paper spacing means have been described. The electrical features of the feeding means will now be explained, with particular reference to the circuit, Figs. 11 and 11a:

60 Before going into the circuit, it may be noted that for the present case, the machine is set for listing, that is, for printing each tabulating cycle. As disclosed in Patent 1,976,617 when setting the machine for listing, a handle 177 (Fig. 1a) is moved to dotted line position. Handle 177 is fast to a shaft 178 rigidly provided with a yoke 179 swiveled to a slideable rod 180 which carries a wedge block 183. Wedge block 183 lies under the free, bent, end of an arm 187 rotatably carried by a shaft 175.

70 Arm 187 is provided with an insulating stud engaging the bottom of a spring contact blade 188a carrying one of contacts 188, the other of which is on a blade 188b. Blade 188a also has a special insulating stud 188c engaged with the bottom of a special blade 188d. Blade 188d car-

ries a special contact point 188', the companion point of which is on a special blade 188e. When the machine is set for listing, handle 177 is moved to dotted line position, and through shaft 178, yoke 179, and rod 180, wedge block 183 is advanced to cam blade 188a upwardly. Through insulating stud 188c, blade 188a when it moves up, also raises special blade 188d to close special listing contacts 188' (see Fig. 1a). The machine, in the present case, being set for listing, special 10 list contacts 188' (see also Fig. 11a) are now closed.

Initially, with main switch S (Fig. 11) open, solenoids 531 and 544 of the traveling and stationary grippers are deenergized, and the paper 15 or sheet RS is free to be inserted in position, as previously explained. The sheet is so adjusted as to place the first line of the heading space of a record form at the printing line.

Main switch S is now closed. Motor M of the 20 feeding attachment is directly across the opposite sides of the current supply, and closing of the main switch immediately starts the motor running. Consequently, magnetic clutch disks 25 509 and 513 are in constant rotation.

Referring to Fig. 11a, when main switch S is closed, the exciting coil 581 of magnetic brake disk 580 is immediately energized by the following circuit:

Brake circuit

30

From the left side of the line, through exciting coil 581, normally closed relay contacts J-1 and to the right side of the line.

Accordingly, brake disk 580 is initially engaging brake disk 582 to prevent accidental rotation 35 of shaft 510 by constantly rotating clutch disks 509 and 513.

Upon closing of switch S, the solenoids 544 of the stationary grippers SG are immediately energized by the following circuit:

Stationary gripper circuit

From the left side of the line, through solenoids 544, normally closed relay contacts A-2 and E-2, manual release contacts 610, and to the 45 other side of the line.

Momentarily, closing of switch S also causes energization of solenoids 531 of the traveling grippers by the following circuit:

Traveling gripper circuit

50

From the left side, through solenoids 531, initially closed stationary gripper contacts 591, and through release contacts 610 to the right side of 55 the supply.

However, when the stationary gripper solenoids are energized, one of them causes contacts 591 to open, as previously described, so that the circuit through the traveling gripper solenoids 531 is 60 broken.

At this time, therefore, the stationary grippers will be engaging the record sheet RS while the traveling grippers will be released from the record sheet.

65 The operator now initiates operation of the tabulating machine, in the manner explained in Patent 1,976,617. During the first tabulating cycle, the first card of the first group is fed to the upper brushes UB (Fig. 11). During the second 70 tabulating cycle, the first card is fed to the lower brushes LB and the second card to the upper brushes UB.

During the third tabulating cycle, the first card is fed past the lower brushes and the latter sense 75

the perforations on the card to control the positioning of type bars 212 (Fig. 1). After the item reading period 9 to 0 of the third tabulating cycle (Fig. 10), the first item is printed in accordance 5 with the positioning of type bars 212 under control of the first card.

Since the first item printing does not take place until the third tabulating cycle, it is desirable to prevent feeding operation until after the 10 first item has been printed in the third tabulating cycle.

As disclosed in Patent 1,976,617, the first card closes lower card lever contacts 59 at the end of the second tabulating cycle. Closing of contacts 15 59 energizes lower card lever relays LCL through the following circuit (Fig. 11):

Lower card lever circuit

From the right side of the line, through lower 20 card lever contacts 59, relays LCL, and to the left side of the line.

Contacts 59 open intermediate a tabulating cycle, but during this open period of contacts 59, cam contacts L6 closed to shunt contacts 59 through lower card lever relay contacts LCLb, 25 cam contacts L6, and to the right side of the line.

Thus, relays LCL remain energized until the last card passes the lower brushes.

30 When relays LCL are energized at the end of the second tabulating cycle, one of them closes relay contacts LCLm (Fig. 11a). This initiates operation of the feeding attachment. Assume traveling carriage 522 to be initially at an intermediate point of its travel between the front and rear rails. As already explained, the stationary grippers were energized upon closing of main switch S to grip the paper. Further, the traveling grippers are now released from the paper. 35 Also, brake disk 580 is now acting on disk 582 to prevent rotation of shaft 510 by either the reverse clutch disk 509 or the advance clutch disk 513, both of the latter now being in continuous rotation.

40 When relay contacts LCLm close at the end of the second tabulating cycle, the following circuit is formed (Fig. 11a):

Circuit f.—From the right side of the line, through relay contacts LCLm, list contacts 188', 50 normally closed relay contacts A-1, relay J, and to the left side of the line.

55 Energization of relay J results, opening contacts J-1 to break the circuit of brake coil 581. Shaft 510 is thereby released from the braking disk 580.

Simultaneously with formation of circuit f, the following circuit is formed through exciting coil 514 of the reverse clutch:

Reverse clutch circuit

60 From the right side of the line, through relay contacts LCLm, list contacts 188', normally closed relay contacts B-1, coil 514, and to the left side of the line.

65 As a result, the reverse clutch is rendered effective to rotate shaft 510 in a direction to return the traveling carriage 522 to the starting point. When the carriage reaches the starting point, it closes normally open front rail contacts 572, causing the following circuit to form (Fig. 11a):

Circuit g

From the right side of the line, through contacts LCLm, contacts 572, relays Q, C, B, and A, 75 and to the left side of the line.

Circuit g energizes relay C to close stick contacts C-1, which are in series with normally closed rear rail contacts 576 to form a shunt around front rail contacts 572. Consequently, when the carriage advances from the starting point, as will be later explained, causing contacts 572 to open, a closed stick circuit g1 through relays A, B, and C is maintained through stick contacts C-1 and rear rail contacts 576. This stick circuit is closed until the carriage reaches 10 the end of its forward stroke, at which time it opens the rear rail contacts 576.

Circuit g and the stick circuit g1 energize relay A to open contacts A-1 in circuit f of relay J. The circuit through relay J can be made now 15 only through relay contacts D-1 which do not close except at feeding intervals, as will be brought out later. With relay J deenergized by the opening of circuit f, contacts J-1 close to re-form the circuit through brake coil 581. At 20 the same time, relay B has been energized by circuits g and g1 to open contacts B-1 in the circuit of reverse clutch coil 514. Consequently, the motor M stops further attempt to rotate shaft 510 in the carriage returning direction, 25 while the brake 580-582 becomes effective to prevent accidental movement of shaft 510 and of the carriage 522.

Energization of relay A by circuits g and g1 also opens contacts A-2 in the circuit of the 30 stationary gripper solenoids 544, causing the stationary grippers to release the paper. As a result of deenergization of the stationary gripper solenoids, contacts 591 close to form the circuit through the traveling gripper solenoids 531. 35 There is a slight lag between the release of the sheet by the stationary grippers and the closing of contacts 591. To cause the traveling grippers to grip the sheet without any lag at all relative to the release of the sheet by the stationary grippers, relay B, energized by circuits g and g1 closes relay contacts B-2 which shunt contacts 591. The circuit of the traveling gripper solenoids is thus completed through shunt contacts B-2 simultaneously with opening of contacts A-2 to 40 break the circuit of the stationary solenoids 544, and without waiting for contacts 591 to close.

Relay C not only closes stick contacts C-1 but also closes relay contacts C-2 (Fig. 11a), which remain closed for the duration of the advance 50 or forward stroke of the carriage.

The conditions after the second tabulating cycle and before the third tabulating cycle are as follows:

The traveling carriage 522 is at the starting 55 point; relays A, B, and C are energized; the brake 580-582 is acting to keep the shaft 510 and, thereby, the carriage, stationary; the stationary grippers have released their hold on the sheet RS; and the traveling grippers have 60 gripped the sheet.

The sheet RS, as explained before, has been preliminarily adjusted with the first line of the head portion of a bill form or the like in printing position, and at the end of the second tabulating cycle and until after the printing operation effected during the third tabulating cycle, 65 the paper remains in the first heading line position.

The first few cards of each minor group contain 70 the head data. The last head data card also has a special perforation, preferably in the X index point position of a selected card column. Following the head data cards, the remaining cards of a minor group contain detail or individ-

ual items to be listed or printed each tabulating cycle.

During the third tabulating cycle, the first head data card is passing the lower brushes LB which sense the items on the latter card to control print magnets 223 for positioning the type 218 for printing the first head items. A printing operation by hammers 224 is then effected to cause the type at printing position to print the first head card items in the first line of the head portion of a bill form of sheet RS. The printing operation is complete shortly after the "0" cycle point (Fig. 10) of the tabulating cycle and before special cam contacts L38 close. When the latter contacts close, the following circuit is completed (Fig. 11a).

Circuit h—Feeding impulse

From the right side of the line, through contacts LCLm, list contacts 188', contacts L38, relay contacts C—2 (now closed), relays F, E, D, and V to the left side.

Energization of relay D closes contacts D—1, which are in parallel with the now open contacts A—1. As a result, circuit f through relay J is made through contacts D—1, causing contacts J—1 to open. Opening of contacts J—1 breaks the circuit of the brake coil 581, freeing shaft 510 for movement.

Relay E, energized by circuit h, opens safety contacts E—2 in the circuit of the stationary grippers to make sure that the stationary grippers are released from the paper.

Relay E also closes contacts E—1 to form the following circuit (Fig. 11a):

Advance clutch circuit.—From the left side of the line, through advance clutch coil 515, contacts E—1, and to the right side.

With clutch coil 515 energized, clutch disk 513 is effective to rotate shaft 510 in a direction to advance carriage 522. Initially, with the carriage at the starting point, rollers 562 of contact levers 556 and 557 are on high parts of their respective total and line space bars 564 and 565. Consequently total and head space contacts 559 and line space contacts 560 are initially open. Cam contacts L38 remain closed long enough to cause the carriage to advance the distance required to bring the rollers 562 of the line space contacts 560 off a projection and into a depression 565' of bar 565. As a result, line space contacts 560 are closed.

The closure of line space contacts 560 shunts the circuit of relays V, D, E, and F directly to the right side of the line, by-passing contacts LCLm, 188', and L38 of circuit h. The shunt circuit through contacts 560 may be referred to as the line space shunt. The line space shunt maintains relays V, D, E, and F energized after cam contacts L38 open and as long as the roller 562 of the line space contacts is traveling in a depression of the line space bar. When roller 562 rides out of the depression 565', line space contacts 560 open, and the carriage advance is interrupted. The next line of the heading of the bill form is now in printing position.

In above manner, successive tabulating cycles will cause printing of the heading items derived from the head data cards and initiate operation of the feeding mechanism to line space the record form to an extent controlled by contacts 560 and bar 565. The last head data card has an X hole, as previously stated. At the time that the X hole is being sensed by a brush LB of the lower

analyzer, special cam contacts L—42 close to establish the following circuit:

Relay K circuit

From the right side of the line (Fig. 11), through lower card lever contacts 59, make and break contacts 61, common 56 of the lower analyzer, the brush LB sensing the X hole, plug socket 300 connected to the brush, a plug connection (not shown) from this socket 300 to a special plug socket 615 (Fig. 11a), cam contacts L—42, a special relay K, and to the left side of the line.

Relay K is energized to close holding contacts K—1 to form a stick circuit after contacts L—42 open, the stick circuit being from the left side of the line, through relay K, contacts K—1, cam contacts L—41, and to the right side.

Relay K also closes contacts K—2 in series with head and total space contacts 559. The closure of contacts K—2 occurred under control of an X hole in the last heading card after the last head item, taken from this card, had been printed. At this time, roller 562 of total-head space contacts 559 is in a notch of bar 564, so that contacts 559 are closed. When contacts K—2 close, the following circuit is formed (Fig. 11a):

Head to detail spacing circuit

From the left side of the line, through relays V, D, E, and F, contacts C—2, contacts 559, relay contacts K—2, and to the right side of the line.

Relay E is energized to close contacts E—1 for causing energization of the advance clutch. The carriage now advances as long as the roller 562 of the head and total space contacts 559 rides in a notch 564' of bar 564. The notch is of such length as to cause the carriage to bring the first line of the detail part of the record form to the printing position. At this point, roller 562 of contacts 559 leaves notch 564' and rides onto a projection of bar 564, causing contacts 559 to open and break the head to detail spacing circuit. The carriage remains in the first detail item position during the next tabulating cycle. Before contacts L—38 close during the latter cycle, cam contacts L—41 open to break the stick circuit through relay K. This transfers the feeding control to the line spacing contacts 560. The successive detail items are then printed and the record form line-spaced each tabulating cycle under control of the feeding impulse circuit and of contacts 560.

When the last detail card of a group is passing brushes LB, the first card of the next group is passing brushes UB. The minor group classification items will be found by brushes UB and LB to disagree, one or more of contacts 359b will remain open (Fig. 11), so that when cam contacts L9 and L10 open, there will be no shunt path for the circuit a and the latter will open. As a result, minor control relay 367 (Fig. 11) will be deenergized, permitting normally closed relay contacts 367f (Fig. 11a) to close. This occurs when cam contacts L9 and L10 open, which is after the item analyzing and printing period of the tabulating cycle. Roller 562 of contacts 559 is now in a notch of bar 564 and contacts 559 are closed. When contacts 367f also close, the following circuit is completed (Fig. 11a).

Total spacing control

From the right side, through lower card lever contacts 59, line 354, switch 617, contacts 367f, line 618, total-head space contacts 559 (still

closed), contacts C-2, relays F, E, D, V, and to the left side of the line.

The total space control circuit energizes relay E to close contacts E-1 and complete the circuit of advance coil 515.

The carriage, therefore, advances until the roller 562 of the total-head space contacts 559 rides up on a projection of control bar 564. Contacts 559 then open to break the total space control circuit and the carriage comes to rest with the predetermined total line of the record form at printing position.

It will be recalled that the total spacing operation was initiated by a change in card group 15 detected by the breaking of circuit a when cam contacts L8, L10 opened, shortly after the 11 point of the tabulating cycle (see Fig. 10). The breaking of circuit a also causes deenergization of motor control relay 338 (Fig. 11) to open contacts 338a and close contacts 338b. Closing of contacts 338b is effective, when cam contacts L3 close near the end of the tabulating cycle, to 20 initiate the normal auto reset circuit d, provided that the total spacing operation has been completed.

The total spacing circuit energized relays V, D, E, and F. Relay E by closing contacts E-1 initiated carriage advance.

Relay D, in addition to closing contacts D-1 30 of circuit f, also closes contacts D-2. If the total spacing operation which started between the 11 and 12 cycle points has not been completed before cam contacts L3 close near the end of the tabulating cycle, then the closure of contacts D-2 will overlap closure of cam contacts 35 L-40 (see Figs. 10 and 11a). Consequently, the following circuit will form (Fig. 11a):

Circuit i

From the right side, through contacts L40, contacts D-2, relays I and H, and to the left side.

Relay I closes holding contacts I-1 to form a stick circuit through serially connected normally closed special printing cam contacts P16 and tabulating cam contacts L39.

Relay H opens contacts H-2 in auto reset circuit d, preventing completion of the latter through the normal path which includes contacts 50 H-2 and cam contacts L3 (see Fig. 11). At the same time, relay H closes contacts H-2'.

Relay F has also been energized by the total spacing circuit, and opens contacts F-2 in series with contacts H-2'.

Thus, although the tabulating cycle during which a group change occurred and in which the total spacing operation began comes to an end, the normal auto reset circuit d cannot be completed unless the total spacing operation for bringing the predetermined total line to printing position has been completed before closing of contacts L40. The total spacing operation is completed when roller 562 of contacts 559 rides onto a tooth of bar 564. At this point, the predetermined total line of the bill form is in printing position, contacts 559 open to break the total space circuit and relays V, D, E, and F are de-energized. However, relay H is still energized through the stick path of circuit i.

With deenergization of relay F, contacts F-2 close and since contacts H-2' are still closed, auto reset circuit d is completed through a shunt path around contacts L3, this shunt path being through relay contacts H-2' and F-2.

A total print and reset cycle now takes place,

near the beginning of which contacts P16 open to break the stick circuit of relays I and H. Printing of the total is effected during the total print and reset cycle on the predetermined total line. While this is taking place, the roller 562 5 of contacts 559 is on a tooth of bar 564 and contacts 559 are open. Following the total printing, special cam contacts P15 close to complete the following circuit (Fig. 11a):

Total to head space initiation circuit

10

From the left side, through relays V, D, E, F, contacts C-2, normally closed relay contacts Q-1, contacts P-15, list contacts 188, and lower card lever relay contacts LCLm, to the right 15 side.

Relay E is energized, closing contacts E-1 to complete the advance clutch circuit. The above circuit endures until cam contacts P-15 open, and is of such duration as to advance the carriage until roller 562 of total-head space contacts 559 moves off the tooth of bar 564, on which it had been resting during the total printing operation, and into the succeeding notch 564'. Contacts 559 thereupon close. Group control relay contacts 367f are still closed, and do not open until cam contacts P1 and P8 close near the end of the reset cycle (see Fig. 10) to close circuit a. With contacts 367f and 559 closed, the total to head space operation initiated by the closing of contacts P15 is continued under control of a total to head spacing circuit, which is the same as the total space control circuit previously traced.

Near the end of the reset cycle, cam contacts 35 P1, P8 close to reestablish the group control circuit a. The latter causes contacts 367f to open. If the total to head space operation which brings the first heading line of the next bill form to printing position has been completed by the time 40 contacts 367f open, then the roller 562 of contacts 559 will be on a tooth of bar 564 and the opening of contacts 367f will not interfere with the correct total to head spacing operation of the carriage. However, if the carriage has not 45 yet brought the first head line of the next bill form to printing position, opening of contacts 367f will occur while contacts 559 are still closed. In order to then prevent the carriage feed from 50 being interrupted, a shunt circuit for the total to head space circuit is completed. Just before cam contacts P1, P8 close, special reset cycle contacts P18 close. Contacts P18 are in series with relay contacts V-1, closed now due to energization of relay V by the total to head space control circuit. If the total to head space operation 55 has been completed before contacts P18 close, then relay V has been deenergized, to open contacts V-1. If the total to head space operation has not been completed when contacts P18 close, then, contacts V-1 are also closed and the following circuit is completed (Fig. 11a):

Circuit j

65

From the left side of the line, through contacts V-1, contacts P18, a relay N, and to the right side of the line.

Relay N is energized by circuit j to close stick contacts N-1, which shunt contacts P18, 70 to hold circuit j after the latter contacts open. Relay N also closes relay contacts N-2 which shunt the group control contacts 367f. With total-head space contacts 559 still closed, the following circuit is formed (Fig. 11a):

75

Circuit k

From the right side of the line, through lower card lever contacts 59 (Fig. 11), line 354, relay contacts N-2, line 618, contacts 559, contacts C-2, relays F, E, D, V, and to the left side of the line.

Circuit k keeps relay E energized until the carriage brings the first heading line of the next bill form to printing position. When that happens, contacts 559 open and circuit k breaks to cause the carriage advance to stop. Also, with circuit k broken, relay V is deenergized and its contacts V-1 open to break the stick circuit of relay N. Contacts N-2 thereupon open, so that circuit k cannot form again unless contacts V-1 and P18, during the next total print cycle, should be closed simultaneously.

Cam contacts P1, P8 close near the end of the 20 reset cycle to re-form circuit a. Circuit a energizes relay 367 to open contacts 367f. At the same time, circuit a energizes motor control relay 338 to close contacts 338a. If the carriage feed to the head space position of the next bill 25 form has been completed, then the normal auto start circuit c will be completed through contacts P2, following closing of contacts 338a. To prevent initiation of the tabulating operations on the new group of cards until the preceding total to head space feed has been completed, circuit c includes special relay contacts H-1. Upon energization of relay D by the total to head space circuit, contacts D-2 close. Special reset cam contacts P17 close near the end 30 of the reset cycle just before cam contacts P1 and P8 close. If the total to head space feeding has not been completed by the time cam contacts P17 close near the end of the reset cycle, then closure of contacts D-2 overlaps closure of cam contacts P17. As a result, a circuit is established through relays I and H (Fig. 35 11a).

Relay H opens contacts H-1 (Fig. 11) of auto start circuit c to prevent normal start of new 40 tabulating cycles. Relay H also closes contacts H-1'. Relay I closes holding contacts I-1 to form a stick circuit through special reset cycle contacts P16 and tabulating cam contacts L39.

50 Relay F of the feeding circuit opens contacts F-1 in series with contacts H-1'. Also in series with contacts F-1 and H-1' are relay contacts B-3 of relay B energized by circuits g and g1. As long as relay B is energized, relay contacts B-3 are closed.

When the total to head space feed has been completed, contacts 559 open, breaking the circuit through relays V, D, E, and F. Contacts F-1 thereupon close and since contacts H-1' 55 are still closed, the auto start circuit is routed through contacts B-3, F-1, and H-1' (Fig. 11a) shunting contacts P2 and H-1. The machine now goes through a new series of tabulating cycles. During the first of the new series of 60 tabulating cycles, cam contacts L-39 break and open the stick circuit through relays H and I.

Provision is made for a special feeding operation when the number of detail items exceeds the maximum number of lines allotted thereto 70 on the record form. As indicated in Fig. 9, the last detail line of a record form is the line above the predetermined total line. After the printing of a detail item on this last detail line, if a group change has occurred, then contacts 367f (Fig. 75 11a) will be closed, and the carriage will be fed

under control of total and head space contacts 559 to the predetermined total line. On the other hand, if the card group is still the same, indicating that more items relating to the group are to be listed, then contacts 367f do not close. 5 However, when cam contacts L38 close, the feeding impulse circuit h is closed, followed by a line spacing operation under control of line space contacts 560, as previously explained. This single line feed brings the roller 562 of the overflow 10 contacts 558 and 558' into a depressed portion of bar 563, causing contacts 558 and 558' to close.

Special cam contacts L43 make for a short interval just before the 15 cycle point (Fig. 10) and with overflow contacts 558' closed, a circuit 15 is completed through relay K as follows (Fig. 11a):

Overflow circuit of relay K

From the left side, through relay K, normally 20 closed contacts R-1, overflow contacts 558', contacts L43, cam contacts L41, and to the right side.

This circuit energizes relay K which closes stick circuit contacts K-1 which by-pass contacts 25 R-1, 558', and L43 to maintain the relay K energized until contacts L41 open. Relay K also closes relay contacts K-3 to complete the following circuit (Fig. 11a):

Overflow feed

30

From the left side, through relays V, D, E, F, contacts C-2, overflow contacts 558, contacts K-3, and to the right side.

Relay E is energized to cause advance of the 35 carriage which continues until roller 562 of the overflow contacts rides out of notch 563' of bar 563 and onto projection. When this happens, overflow contacts 558 and 558' open and the carriage stops with the first detail line of the 40 next bill form in printing position.

The overflow items are now printed successively in the detail portion of the second bill form. When the group changes, total spacing is effected, as explained, and brings the total line of the 45 second form to printing position.

In order to make certain that the overflow feed has been completed before the printing of the first overflow item takes place, relay contacts I-2 have been provided in shunt circuits 50 c1 and c2 to interrupt the tabulating operations at the end of the tabulating cycle during which the overflow feed began unless the overflow feed is completed by the end of the latter cycle.

It will be recalled that if the feed circuit is 55 still in effect near the close of the tabulating cycle, that contacts D-2 of relay D in the feed circuit will still be closed when cam contacts L40 make, causing circuit i to be completed. This circuit energizes relays H and I, the former controlling relay contacts in the auto reset and the auto start circuits, as previously explained. Relay I, in addition to closing stick circuit contacts I-1 also opens relay contacts I-2 in shunt circuits c1 and c2 of the tabulator. As a result, the 65 tabulating clutch magnet 22 and the tabulating motor TM are deenergized causing the tabulating mechanism to stop at the end of the cycle.

Relay H, being energized, has closed contacts H-1' in the auto start shunt circuit. Relay F 70 of the feeding circuit has opened contacts F-1. When the overflow feed has ended, contacts 558 open, causing the feed circuit to break and relay F to be deenergized. Contacts F-1 thereupon close and complete the auto start circuit c 75

through the shunt contacts B-3, F-1, and H-1' around contacts P-2 and H-1. The machine automatically resumes tabulating operations. At the beginning of the first of the resumed tabulating cycles, contacts L39 in the stick circuit of relays I and H open and the relays are deenergized. Contacts I-2 close to render shunt circuits c1 and c2 operative and contacts H-1' open to break the shunt path of auto start circuit c. During the first resumed tabulating cycle contacts L41 of the holding circuit of relay K also open to cause deenergization of the relay K.

The overflow circuit of relay K can be closed only when no card group change has occurred. If a group change occurs, relay contacts R-1 in series with overflow contacts 558' open to prevent energization of relay K. To open contacts R-1 when a group change occurs, relay R is energized by a circuit in parallel with the total space circuit. It will be recalled that a group change is sensed by opening of contacts L9, L10 of circuit a at the 11 cycle point. When circuit a breaks, group control relay contacts 367f (Fig. 11a) close. When this occurs, the total feed circuit is completed. Simultaneously, the following circuit is completed.

Circuit L

From the right side, through lower card lever contacts 59 (Fig. 11), line 354, contacts 367f (Fig. 11a), a line 619, relay R, and to the left side.

Energization of relay R closes stick contacts R-2 to form a holding circuit through contacts R-2 and normally closed relay contacts K-4.

Relay R also opens contacts R-1 in the overflow circuit of relay K. Consequently, relay K cannot be energized although overflow contacts 558 and 558' and cam contacts L43 close. Accordingly, the relay contacts K-3 do not close and the carriage feed is not placed under control of the overflow contacts 558 but remains under control of the total-head space contacts 559.

The overflow circuit through relay K should not become operative until the last detail line of a bill form has been printed upon.

During a total print cycle, relay contacts R-1 are open to render the overflow circuit of relay K ineffective. The total to new head space feed takes place under control of total-head space contacts 559 and when the carriage has advanced so as to bring the first heading line of the new bill form to printing position, contacts 559 open and the carriage feed stops. Overflow bar 563 is notched along the carriage travel from the last detail line of the first form to the first detail line of the second form. Consequently overflow contacts 558 and 558' are closed during the first tabulating cycle following the total print cycle. During this first tabulating cycle, contacts L43 close and should relay contacts R-1 be closed at that time, the overflow feed circuit of relay K will form. It is to prevent making of this circuit at this time that the stick circuit of relay R has been made. This stick circuit which goes through contacts R-2 and closed contacts K-4 does not open until the carriage has moved the first detail line of the bill form to printing position. When the carriage reaches this position, overflow contacts 558 and 558' open.

It will be recalled that the last head card has an X hole and that analysis of the X hole forms a circuit through relay K to close contacts K-2 for rendering total-head space contacts 559 effective to close the head to detail feeding circuit.

When relay K is thus energized, it opens contacts K-4 in the stick circuit of relay R, and thereafter until a group change is sensed, contacts R-1 remain closed. Hence, the overflow circuit of relay K will be able to form again should the printing in the last detail line of the bill form be unaccompanied by a change in card group.

Should the group change occur when the first detail line is printed upon, contacts 559 being open then, the total space circuit will not form immediately upon detection of the group change with consequent closure of contacts 367f. The usual feeding impulse circuit h will form when contacts L38 make, and cause the carriage to advance, with the result that the roller 562 of contacts 559 moves into a depression of bar 564 and the latter contacts close to complete the total space circuit through contacts 367f.

If, after printing any item, heading, detail, or total, the following feed step brings the carriage to the end of its forward stroke, the rear rail contacts 516 break, causing the stick circuit g' through relays A, B, and C to break. Contacts C-2 in the feed circuit open and relay E is therefore deenergized to stop the carriage advance by opening contacts E-1 in the advance clutch circuit. Simultaneously, relay E permits contacts E-2 to close. Also relay A having been deenergized, contacts A-2 close, thereby completing the circuit of the stationary gripper solenoids 544, as a result of which the stationary grippers clamp the sheet against movement. Relay B also having been deenergized, contacts B-2 in the traveling gripper circuit open, but the shunt circuit of the traveling grippers, which is through stationary gripper contacts 591, is still closed and does not open until the stationary grippers have nearly taken hold of the record sheet. The traveling grippers thus maintain their grip on the record sheet until just before the stationary grippers take hold.

Deenergization of relay B permits relay contacts B-4 to close and form the circuit of reverse clutch coil 514. Relay A also has been deenergized to permit relay contacts A-1 in circuit f to close. Circuit f is formed, energizes relay J, and the latter opens contacts J-1 in the brake coil circuit to disable the braking means. The carriage now is driven in a reverse direction, back to its starting point.

The feed step which advanced the carriage to the limit of its forward stroke, where it broke circuit g', began after a printing operation. If the machine is going through a tabulating cycle, then the cam contacts L-40 close near the end of the cycle and if the reverse feed has not been completed by the time cam contacts L-40 close, then initiation of the next tabulating cycle will be prevented. For this purpose, normally closed relay contacts A-3 are placed in series with contacts L-40. When circuit g' was broken, relay A was deenergized and permitted contacts A-3 to close. With contacts A-3 and L-40 simultaneously closed, a circuit is completed through relays H and I. Relay I closes contacts I-1 to form the stick circuit through cam contacts P-16 and L-39.

Relay I also opens contacts I-2 (Fig. 11) to break the shunt circuits c1 and c2 to interrupt tabulating operations at the end of the tabulating cycle during which the reverse feed began. Relay H opens contacts H-1 and closes contacts H-1' of the shunt path around contacts P-2 (Fig. 11). This shunt path cannot be completed until relay

contacts B-3 close, which does not happen until relay B is energized. While the carriage is on its reverse stroke, relay B is deenergized.

When the carriage finishes its reverse stroke and reaches the starting point, circuits g and g' form and energize relay B. Contacts B-3 then close and since contacts F-1 and H-1' are also closed, the auto start circuit around cam contacts P-2 is completed and the machine resumes tabulating operation.

In the above manner, the start of a new tabulating cycle is prevented until the reverse feed begun during the preceding tabulating cycle has been completed.

15 The reverse feed usually takes place after a total printing operation effected during a total print and reset cycle. The total to head space initiating circuit is formed after the total printing operation by closure of contacts P-15. The total 20 to head space circuit then operates due to closure of contacts 559. As explained before if the total to head space advance operation has not been completed by the time cam contacts P-17 close, then relays I and H are energized to prevent formation 25 of the auto start circuit. If during this advance operation, the carriage reaches the limit of its forward stroke before cam contacts P-17 close, then relay D will be deenergized, and the circuit of relays H and I cannot be made through 30 relay points D-2. However, since circuit g' has been broken, relay A is deenergized, relays points A-3 close, and if the reverse feed has not been completed before cam contacts P-17 close, relays H and I will be energized. Contacts H-1' 35 and F-1 of the auto start shunt will be closed but relay points B-3 will be open due to deenergization of relay B. When the carriage completes its reverse movement, relay B is energized, closes contacts B-3 and the auto start shunt is 40 closed to initiate a tabulating cycle.

SUMMARY

In starting a new series of operations, the operator closes main switch S (Fig. 11). This sets 45 motor M in rotation (Fig. 11a), causes the stationary grippers SG to grip the record sheet, and the brake 580-582 to act on shaft 510. The operator then depresses the reset key to close reset key contacts R (Fig. 11), to form the following 50 circuit:

First reset cycle start.—From the left side of the line, through cam contacts F3, relay 348, reset key contacts R, closed relay contacts 339b, line 345, contacts I-2, cam contacts L2, and to 55 the right side of the line.

Relay 348, being energized, closes relay points 348a to shunt reset key contacts. Closing of points 348a also forms a circuit from the right side of the line, through points 348a, cam contacts L4, reset clutch magnet 197, contact 384c, P3, and to the left side.

Closing of contacts 287 by magnet 197 forms a circuit through reset motor RM.

The machine then goes through its first reset 65 cycle.

During the first reset cycle, cam contacts P7, P8 close to form circuit a. The machine then stops. The operator now depresses the start key to close start key contacts ST (Fig. 11), forming 70 the following circuit:

First tabulating cycle start

From the right side of the line, through contacts 338a (now closed), contacts SP, contacts 75 ST, relay 339, contacts 27, tabulating clutch mag-

net 22, contacts P1, and to the left side of the line.

Magnet 22, being energized, opens contacts 27, shunting the circuit through relay 340, which closes contacts 340a to complete the circuit of tabulating motor TM. The machine now goes through a tabulating cycle, at the end of which it stops due to deenergization of relay 339 and clutch magnet 22 as a result of momentary opening of contacts L2 in shunt circuit c2. The operator now depresses the start key a second time, closing contacts ST to establish another tabulating circuit. The machine then goes through a second tabulating cycle. During this cycle, lower card lever contacts LCLm (Fig. 11a) close, 15 which as previously described causes the reverse clutch circuit to be formed and the brake circuit to be broken. The carriage then is returned to its starting point, where it closes circuit g through relays A, B, C, and Q. Relay B opens contacts 20 B-1 to break the reverse coil circuit. Contacts B-2 close to form the traveling gripper circuit, and contacts A-2 open to break the stationary gripper circuit.

The machine again stops at the end of the second tabulating cycle, due to opening of shunt path c2 when cam contacts L2 open. During the second tabulating cycle, circuit a is broken when cam contacts L10, L9 open. Also, upper card lever contacts UCLe are opened by energization 30 of relay UCL which occurred at the end of the first tabulating cycle. With contacts UCLe open, the shunt path comprising contacts LCLg and UCLe around contacts L10, L9 is open, and consequently circuit a is broken during the second 35 tabulating cycle, causing deenergization of relay 338 and closure of relay points 338b.

Closure of relay points 338b forms the normal auto reset circuit d. The machine then goes through a second reset cycle. During this reset 40 cycle, cam contacts P15 close (Fig. 11a) but the total to head space initiation circuit through relays V, D, E, and F cannot form because relay points Q-1 are now open as a result of the carriage still being at the starting point, and relay Q consequently being energized by circuit g.

Accordingly, the carriage remains at the starting point during the second reset cycle. While at the starting point, roller 562 of contacts 559 is on a high point of bar 564 and consequently, 50 contacts 559 are open and the total to head space feed circuit through these contacts cannot form. Consequently, the carriage remains at the starting point during the second reset cycle. During the latter cycle, circuit a is again formed followed 55 by normal auto start circuit c. The machine then goes through its third tabulating cycle, during which the items of the first card are sensed by the lower brushes LB to control print magnets 223. The first printing then takes place. Following this the feed impulse circuit h forms to initiate line spacing.

The carriage thereupon advances from its starting point, causing circuit g to break and relay Q to be deenergized. Relay points Q-1 65 thereupon close.

In above manner, advance of the carriage and sheet feed are delayed until after the first printing operation, so that the first line of a bill form will be in position to receive the first imprint. 70

The machine continues to go through tabulating cycles until disagreement in group control perforations is found. When this happens, relay 338 is deenergized and normal auto reset circuit d formed provided the spacing to the predeter- 75

mined total line has been completed. If not, then the auto reset circuit shunt including contacts H-2' and F' is closed to initiate a reset cycle when the feed has been completed. During the 5 reset cycle, after total printing, the total to new head space impulse circuit is formed by closure of contacts P-15, followed by a total to head space feed under control of bar 564 and contacts 10 559. If the feed to the new head space has been completed by the time contacts P2 close, then the normal auto start circuit c is established. If not, then when the feed is completed, the auto start shunt including contacts E-3, F-1, and H-1', initiates tabulating operation.

15 Whenever a feed, during a tabulating cycle in which no group change occurred, is not completed by the time contacts L40 close, then circuit i is formed, relay I is energized to open contacts I-2, thereby causing the tabulating mechanism to stop 20 at the end of the tabulating cycle. Resumption of tabulating cycles is then under control of the shunt around contacts P-2 and which includes contacts B-3, F-1, and H-1'.

If a reverse feed of the carriage is not completed 25 by the time either contacts P-17 or L-40 close, then relays I and H are energized through relay points A-3 and the start of a new tabulating cycle is delayed until the carriage reaches the beginning of its forward stroke. When this happens, relay B is energized to close contacts B-3 30 for completing the shunt around contacts P-2.

It is understood that feed control bars 563, 564, and 35 565 are removable and replaceable by bars of different contours to suit different desired conditions of feed.

While the invention has been disclosed as embodied in the form herein shown and explained, it is clear that the invention may also be embodied in other forms, and that variations, changes, and 40 departures may be made from the illustrated form without departing from the scope of the invention. It is therefore intended to be limited only in accordance with the following claims.

What is claimed is:

45 1. In combination; a sheet feeder, actuating mechanism therefor, a circuit, electrical means rendered effective under control of said circuit when closed for effecting actuation of the feeder by the actuating mechanism, a controller having spaced circuit enabling portions and intermediate the latter having circuit disabling portions, a device driven concomitantly with the feeder for successively cooperating with said portions, and means controlled by cooperation of the aforesaid device with an enabling portion of the controller for closing said circuit to cause the electrical means to render the actuating mechanism effective to drive the sheet feeder and the aforesaid device until the latter moves into cooperation with 50 the following circuit disabling portion of the controller.

55 2. In combination; a sheet feeder, actuating mechanism for the feeder, a circuit, electrical means rendered effective by closing of said circuit for causing the actuating mechanism to advance the sheet feeder, a controller having spaced circuit enabling portions and intermediate the latter having circuit disabling portions, a device operated by the actuating mechanism for successively 60 cooperating with said portions, means set in operation while the feeder is at rest with the aforesaid device in cooperating relation to a circuit disabling portion of the controller for momentarily closing said circuit through one path to render the electrical means operative for causing the me-

chanism to move the aforesaid device out of cooperation with the circuit disabling portion and into cooperation with the following circuit enabling portion of the controller, and means controlled by cooperation of the device with the latter enabling portion to close said circuit through a different path than the first-mentioned path to thereby cause the feeder and device to be actuated by the mechanism until the device moves out of cooperation with the latter enabling portion and into cooperation with the next disabling portion of the controller.

3. In combination; a traveling gripper for gripping and feeding a sheet during travel of the gripper, electrical means for operating the gripper to grip the sheet, a circuit for said means, an actuator for said gripper to move the latter for advancing the sheet, and means operated by the actuator concomitantly with the gripper for opening and closing said circuit in accordance 15 with the point of travel of the gripper.

4. In combination; a traveling carriage carrying a gripper for gripping and feeding a sheet during travel of the carriage, electrical means for operating the gripper to effectively grip the sheet, a control circuit for said electrical means, a switch in said circuit, and means connected to the carriage for movement concomitantly therewith for controlling opening of the switch at a certain point of the travel of the carriage.

30 5. In combination; a reciprocatably mounted carriage having a sheet gripper, actuating mechanism for reciprocating the carriage, electrical means automatically effective during the forward stroke of the carriage for operating the gripper to grip and feed the sheet, a control circuit for said electrical means, means for automatically opening said circuit at a certain point of the forward stroke of the carriage to thereby cause the gripper to release the sheet, means for thereupon causing the actuating mechanism to move the carriage through its return stroke, and means for automatically reclosing said circuit at the end of the return stroke of the carriage to cause the gripper to grip the sheet again.

45 6. In combination; a reciprocatably mounted carriage having a sheet gripper, actuating mechanism for reciprocating the carriage, means effective during the forward stroke of the carriage for operating the gripper to grip and feed the sheet, means for automatically disabling the first-mentioned means at a certain point of the forward stroke for causing the gripper to release the sheet, and devices automatically controlled by operation of the second-mentioned means 50 when the latter causes release of the sheet by the gripper for enabling the actuating mechanism to move the carriage through the return stroke.

7. In combination; a traveling carriage having 60 a gripper for gripping a sheet, means for rendering the gripper effective for gripping the sheet to feed it during certain portions of the travel of the carriage, alternate gripping means for the sheet released from the sheet while the gripper is 65 gripping and feeding the sheet, means effective at a certain point of travel of the carriage for rendering the alternate gripping means effective to grip the sheet, and means controlled by the alternate gripping means, when rendered effective, for causing the feeding gripper to release the sheet.

8. In a machine having printing means to print items; the combination of a sheet gripper mounted for movement in a forward direction 70

from a starting point, actuating mechanism for the gripper, means for automatically operating the gripper to grip the sheet at the starting point, a feed controller, a device movable synchronously with the gripper and coacting with the controller for causing the actuating mechanism to effect movement of the gripper in the forward direction in successive steps to space the sheet for receiving successive item printings from the printing means, means for automatically releasing the gripper from the sheet at a certain point of the movement of the gripper in the forward direction, and means for returning the gripper in the opposite direction to its starting point, while released from the sheet, and means for rendering the controller and device ineffective, during return of the gripper, to control operation of said actuating mechanism.

9. In a machine in which a variable number of items are successively listed by printing means during listing cycles and in which the printing means prints on a predetermined total line a total of such items during a total cycle which follows the printing of the last item; the combination of sheet feeding means to feed the sheet across the printing means to receive impressions therefrom, means operable during the listing cycle in which the last item is printed for effecting a variable feed of the sheet by the feeding means to bring the predetermined total line to printing position to receive the total imprint, and devices controlled by the sheet feeding means for delaying the total cycle until the latter feed of the sheet has been completed.

10. In combination; a sheet feeder having a forward sheet feeding stroke and a non-feeding return stroke, a drive shaft, a forward clutch between said shaft and feeder to effect movement of the latter along its forward stroke, a reverse clutch between the shaft and feeder to effect the return stroke of the feeder, and means for sensing the positions of the feeder along its forward stroke, electrical means controlled thereby for determining successive periods of effectiveness of the forward clutch, means for sensing the termination of the forward stroke of the feeder, and electrical means controlled by the latter sensing means for rendering the reverse clutch effective.

11. In a machine operating on statistical records the arrival of which at an operating station is preliminarily detected by a card lever; the combination of a sheet feeder, adapted to move in a forward direction to feed a sheet, means to

return the feeder from any advanced position in which it may be at rest to a start position, means for preventing feed of the sheet by the feeder while returning and means controlled by the card lever upon detecting arrival of a record at the operating station for causing the returning means to return the feeder to the start position.

12. In a machine having printing means for printing heading, detail, and total items in predetermined heading, detail, and total zones of a record form; the combination of feeding means for such record forms, means controlling the feeding means for line space operation within the heading and detail zones, fixed control means for determining operation of the feeding means to effect interzone spacing of a form with respect to the printing means from heading to detail zone, from detail zone to total zone, and from total zone to next heading zone, a device cooperating with the fixed control means for governing the extent of aforesaid interzone spacings, a common actuator for the feeding means and the aforesaid device for moving them concomitantly, means operative after the printing of the last heading item for rendering the cooperation of said device with said fixed control means effective to control operation of the feeding means for spacing the form from the heading zone to the detail zone, means operative after printing of the last detail item for rendering cooperation of the device with the fixed control means effective to control operation of the feeding means to space the form from the detail zone to the total zone, and means operative after printing of the total item for rendering the cooperation of the device with the fixed control means effective to control the feeding means for spacing the form from the total zone to the next heading zone.

13. In combination; a sheet feeder, friction drive means capable of moving the feeder any variable extent, a feed controller with successive feed effectuating portions spaced apart by a feed interrupting portion, means controlled by the successive feed effectuating portions for rendering said friction drive means effective to advance the feeder through successive feed steps, a magnetic, friction brake for engaging the friction drive means to prevent operation thereof, and a circuit closed under control of the feed interrupting portion for energizing the magnetic brake to hold the drive means against operation between successive feed steps.
